UNITED STATES PATENT OFFICE.

JULIUS FINCK, OF SAN FRANCISCO, CALIFORNIA.

CASH AND PACKAGE CARRIER.

SPECIFICATION forming part of Letters Patent No. 469,896, dated March 1, 1892.

Application filed November 4, 1891. Serial No. 410,854. (No model.)

To all whom it may concern:

Be it known that I, JULIUS FINCK, a citizen of the United States, residing in the city and county of San Francisco, State of California, 5 have invented an Improvement in Cash and Package Carriers; and I hereby declare the following to be a full, clear, and exact description of the same.

My invention relates to that class of cash 10 and package carriers in which a basket is lifted by suitable hooks into engagement with the forks of a car traveling on a track above.

My invention consists in a novel automatically-operating locking device for securing 15 the cross-head of the basket-bails to the car-forks, in a spring attachment for the ordinary cross-head hook, and in a guard for the car-forks, all of which I shall hereinafter fully describe, and specifically point out in the 20 claims.

The several objects of my improvements will fully appear in connection with their detailed description.

Referring to the accompanying drawings 25 for a more complete explanation of my invention, Figure 1 is a perspective view showing the basket about to be lifted to its engagement with the car-fork. The basket-elevating hooks H are here shown just about to 30 touch the downwardly-projecting portion j' of levers J and to lift the basket, wherefor the locking-pins I are not as yet retracted. One of the slot-walls of the car-fork is shown broken away. Fig. 2 is an elevation showing 35 the parts in engagement, one of the locking-pins I being shown in place and the other withdrawn, being for the purpose of showing its movement.

A is a car mounted on a track B. The car 40 has the downwardly-extending fork a, the arms of which are vertically slotted. In the slot of one arm is the cross-stop a', and in the slot of the other arm and higher up are the cross-stops a² and a³, separated slightly from 45 each other, the upper stop a³ having a top a⁴ extending inwardly.

C is the basket.

D is the basket-bail, and E is the cross-head of said bail. From the under side of the 50 middle portion of the cross-head and between the opposing guide-flanges e is suspended the pivoted hook F. This hook is heavier at the

end f than at the end f', so that the latter end normally lies uppermost and the hook extends when at rest in a position approximating the vertical. Near the heavier end f of the hook on its upper portion is the small shoulder f². 55

H are the basket-elevating hooks, and h are the hoisting-ropes thereof. 60

All the parts are in common use in a well-known system, and it will be sufficient to briefly describe their operation. The basket-elevating hooks H are lowered and fitted under the cross-head E. Then the basket is 65 hoisted until the center of the cross-head enters the lower open end of the car-fork a. At the same time the upper end f' of hook F enters the slot of the fork-arm on that side, and, coming in contact with the cross-stop a' there-in, said hook as it travels upwardly is turned down to a vertical position with its former upper end lowermost. In this position the hook avoids the several stops in the fork, and the cross-head reaches the upper end of the fork. 70

At this time the lower end of the hook has passed the stop a', and the heavier and then upper end of said hook drops outwardly into contact with cross-strip a³, this movement being sufficient to carry its other end f' out into 75 the vertical plane of stop a' into the slot of that fork-arm. Now the basket is lowered slightly, and the hook F moving down its end f' comes down upon the top of cross-stop a', while its end f, being freed from the inner 80 surface of stop a³, falls into the slot between said stop and stop a² and rests on the latter stop. Being then on the two stops a' and a², the hook lies transversely at a slight angle 85 and suspends the basket from the car-fork. 90 Now to disengage the hook the cross-head E is lifted again. This has the effect of causing the heavier end f of the hook, which lies between two stops a² and a³, to turn downwardly, while its lighter end f' turns upwardly. 95 This continues until the top a⁴ of stop a³ comes down into contact with shoulder f² on the hook, which contact positively releases the end f from between stops a² and a³, thus throwing the hook into practically its initial position, 100 in which as it moves downwardly it will avoid all the stops and the cross-head will come freely out from the car-fork. In other words, the hook when turned light end up will avoid

all the stops and when reversed will be caught thereby, and the object of these movements is to reverse and to right the hook as required.

It has been found in practice that the connection is not always made or preserved, and the basket oftentimes drops off, occasioning serious damage to articles below, especially show-cases. The connection will fail to be made if for any reason the normally upper or light end f' of the hook is not upon its entrance engaged by stop a' to effect its reversal as it ascends. This may happen by the upper end sticking and lying so close to the cross-head that it will enter the fork without coming in contact with stop a' . In this case it will not be reversed, and as soon as the basket is released it will fall; as the hook will then simply slip right down through the fork. The connection is often not preserved, even though properly made. This may happen from the jolting of the car or of the basket, which results in the opposite movements of the fork and cross-head, thus effecting the righting or return of the hook and the consequent release of the basket. To overcome these disadvantages, I provide a positive lock, as follows: I am opposing oppositely-moving locking-pins. They enter, play in, and engage elongated slots a' , made vertically in one of the fork-arms. They also play through slots e' in flanges e of cross-head E . They are carried by bearing-plates i , which have shanks i' seated in the cross-head E , which is longitudinally slotted to receive them, and they are pivoted in said slots at the points i'' . Also seated in the slots of the cross-head are levers J , pivoted at their outer ends at j . The inner ends of these levers engage the outer ends of the shanks i' beyond their pivots, and the bodies of said levers project, as shown at j' , below the under surface of the cross-head. The levers are held in and returned to normal position by springs K , acting on their outer ends.

The operation is as follows: When the cross-head E is lifted by the basket-elevating-hooks H , these hooks bear under the projecting body portions j' of levers J and force them up. This causes their inner ends to turn the shanks i' on their pivots i'' , thereby withdrawing their plates i , and thus the locking-pins are separated or withdrawn, and they pass up on each side of the fork-arm. Then the cross-head is first lowered by relieving the pull on the basket-elevating hooks, and the hook F comes to its engagement in the fork a , as heretofore described, and suspends the basket. The latter being thus suspended independently of the basket-hooks H , said hooks relieve the levers J and these throw the locking-pins inwardly through slot a' in the fork-arm. These pins therefore form a positive lock, and no amount of movement of either basket or car will relieve said lock, no matter what effect it may have in righting hook F , as heretofore described; but when the basket-elevating hooks H are again raised they, act-

ing through levers J , withdraw the locking-pins and the disengagement of hook F is effected, as heretofore.

My second improvement is the small spring L . This is secured to the top center of cross-head E and bends down over that side thereof which is contiguous to the upper or lighter end f' of hook F . Its effect is to keep said end out far enough to prevent its sticking close and to insure its engagement with stop a' upon its entrance to the fork. Thus the danger of a failure to make connection is avoided.

My third improvement is in providing a guard for the lower end of fork a . This guard consists of the strips M , secured to the lower ends of the fork-arms and curving upwardly to and secured to said arms above. The lower ends of the fork-arms are usually made flaring to insure the entrance of the basket-bail cross-head; but, notwithstanding this, the cross-head often gets to one side and rides up on the upper surface of the fork-ends; but the strips M prevent this and at the same time they strengthen said fork-arms.

Having thus described my invention, what I claim as new, and desire to secure by Letters Patent, is—

1. In a store-service apparatus, the combination of a way, a carrier permanently located thereon provided with a depending fork having stops on its tines, a receptacle, devices for detachably connecting the receptacle to the car, consisting of a reversible attaching-hook F , pivoted to a cross-head on a bail secured to the receptacle, locking-pins for engaging said hook, and devices for holding the pins against the hook, elevating-hooks to raise and lower the receptacle to and from the car, and connections whereby the locking-pins are withdrawn from contact with the hook F when the receptacle rests on the elevating-hooks, substantially as herein described.

2. In a store-service apparatus, the combination of a way, a carrier permanently located thereon provided with a depending fork having stops on its tines, a receptacle, devices for detachably connecting the receptacle to the car, consisting of a reversible attaching-hook F , pivoted to a cross-head on a bail secured to the receptacle, locking-pins for engaging said hook, devices for holding the pins against the hook, elevating-hooks to raise and lower the receptacle to and from the car, the levers J , seated in and projecting below the cross-head, and connections between said levers and pins, substantially as herein described.

3. In a store-service apparatus, the combination of a way, a carrier permanently located thereon provided with a depending fork having stops on its tines, a receptacle, devices for detachably connecting the receptacle to the car, consisting of a reversible attaching-hook F , pivoted to a cross-head on a bail secured to the receptacle, locking-pins for engaging said hook, devices for holding the pins against the hook, elevating-hooks to raise and lower

the receptacle to and from the car, the pivoted shanks and bearing-plates of said pins, and the levers J, seated in and projecting below the cross-head and engaging said shanks, substantially as herein described.

4. In a store-service apparatus, the combination of a way, a carrier permanently located thereon provided with a depending fork having stops on its tines, a receptacle, devices for detachably connecting the receptacle to the car, consisting of a reversible hook F, pivoted to a cross-head on a bail secured to the receptacle, oppositely-moving locking-pins for engaging said hook, devices for holding the pins against the hook, elevating-hooks to raise and lower the receptacle to and from the car, the pivoted shanks and bearing-plates of said locking-pins, the levers J, seated in and projecting below the cross-head and engaging said shanks, and springs for controlling the levers, substantially as herein described.

5. In a store-service apparatus, the combination of a way, a carrier permanently located thereon and provided with a depending fork, a receptacle, means for detachably connecting the receptacle to the car, consisting of the reversible hook F, pivoted to a cross-head on a

bail secured to the receptacle, the locking-pins and means for holding the same against the hook, elevating-hooks to raise and lower the receptacle, and the spring L on the cross-head for regulating the position of the upper end of the hook, substantially as herein described.

6. In a store-service apparatus, the combination of a way, a carrier located thereon provided with guard-strips M on the lower ends of its arms, a receptacle, means for detachably connecting the receptacle to the car, consisting of a reversible hook F, pivoted to a cross-head on a bail secured to the receptacle, the locking-pins and means for holding them against the hook, the elevating-hooks for raising and lowering the receptacle to and from the car, and connections whereby the locking-pins are withdrawn from contact with the hook F when the receptacle rests on the elevating-hooks, substantially as herein described.

In witness whereof I have hereunto set my hand.

JULIUS FINCK.
